DEMODULATOR

Helmut Pitsch, Berlin, Germany, assignor to
 Telefunken Gesellschaft für Drahtlose Tele-
 graphie, m. b. H., Berlin, Germany, a corpo-
 ration of Germany

Application August 4, 1937, Serial No. 157,245
 In Germany September 30, 1936

1 Claim. (Cl. 250—27)

The demodulation of a carrier with a side band by means of a linear rectifier entails distortions which make themselves felt in the form of combination notes and upper harmonics. This has 5 its cause in the fact that the envelope of the modulated carrier frequency has no sinusoidal form despite the sinusoidal modulation. The application of a rectifier characteristic of parabolic form offers advantages only when the side frequencies control only a very small part of the 10 characteristics, and if the carrier frequency voltage is higher than the voltages of the side frequencies.

In accordance with the invention a demodulation 15 method for single side band telephony is given which operates without distortions and has a wide range of control. The invention resides in that the working point of the grid to which the signalling oscillations are applied is so placed 20 that these oscillations control only a straight portion of the tube characteristic, and that only the carrier frequency is applied to a second grid with whose voltage variation the steepness of the straight tube characteristic varies.

The invention can be practiced on a double 25 grid tube, but more favorable results are obtained when the invention is applied to a tube in which between the two grids a positively biased screen grid exists. The filtering out of the carrier frequency can best be carried out by means 30 of a quartz crystal. Therefore, it will be of advantage to employ the invention in the intermediate frequency part of the receiver, since in this case the filtering means for the carrier frequency need not be varied.

An example of a circuit for practicing the invention is shown in the figure.

The intermediate frequency carrier together with the one side band are applied to the band 40 filter B and then to the first grid 2 of the tube. The intermediate frequency carrier is furthermore filtered out by means of the quartz crystal Q and applied to the third grid 6. The first grid 2 receives a negative biasing potential across the oscillatory circuit and the third grid 6 receives such a potential across the resistor W. The interposed screen grid 4 which is positively biased 45 has the effect that a voltage variation at the third grid 6 tilts about a fixed point the grid voltage-plate current characteristic appertaining to the first grid 2. The last screen grid 8 has the purpose of increasing the amplification.

The arrangement acts such that the carrier frequency modulates the side band frequencies, 55 thereby producing as in case of any modulation

a frequency difference and frequency sum. The difference frequencies represent the desired tone frequencies and this may be utilized from the anode electrode 10. In this method upper harmonics cannot be produced since the operation 5 is not carried out on the curved portion of the tube characteristics, and since it is also not operated on the lower bend of a straight characteristic. For this reason the side band frequencies 10 cannot modulate each other, and combination notes can likewise not be produced by the said side band frequencies.

It should furthermore be pointed out that the use of the invention offers the above mentioned 15 advantages only in the single side band telephony, since in the telephony with two side bands a distortion free demodulation can already be assured by means of linear rectification, the invention therefore relating only to the single side 20 band telephony. It is obvious that the invention 25 can also be used when for the demodulation of a carrier with two side bands only the one side band is employed.

The invention is not confined to the measure 25 of filtering out the carrier frequency, but the carrier frequency may also be produced locally, and then added, for which purpose the demodulation tube may for instance be designed as self oscillating tube such as is customary in the mixer 30 tubes in superheterodyne receivers. The amplification achieved is the higher the larger the amplitude of the carrier frequency is chosen.

I claim:

In a superheterodyne receiver, a demodulator 35 of an intermediate frequency carrier which is modulated by only a single side band frequency, comprising a vacuum tube provided with at least a cathode, a signal control grid, a second grid and an anode, a band-pass filter of intermediate 40 frequency connected between the signal grid and the cathode, a quartz crystal connected between the filter and the second grid for impressing only the intermediate frequency carrier on said second grid, means for applying a negative biasing 45 potential to the control grid for maintaining the operating point of the tube on a linear portion of the grid voltage-plate current characteristic, and means for applying a negative biasing potential to the second grid such that the voltage 50 variations applied thereto will vary the steepness of said tube characteristic about the operating point maintained by the potential on the first grid.
